UNITED STATES PATENT OFFICE.

RUDOLPH G. WIRTALLA, OF NEW YORK, N. Y.

LOOM HEDDLE-FRAME.

SPECIFICATION forming part of Letters Patent No. 729,477, dated May 26, 1903.

Application filed October 24, 1902. Serial No. 128,573. (No model.)

To all whom it may concern:

Be it known that I, RUDOLPH G. WIRTALLA, a citizen of the United States, and a resident of the city of New York, (Long Island City, 5 borough of Queens,) in the county of Queens and State of New York, have invented a new and Improved Loom Heddle-Frame, of which the following is a full, clear, and exact description.

10 My invention relates to improvements in loom heddle-frames of that class wherein a series of heddles are strung on heddle-bars, the latter being stayed in place by hooks attached to the end portions of the frame. 15 Heretofore considerable difficulty has been experienced by operators in adjusting the heddles within the frame and in applying or removing the heddles. This is due, primarily, to the attachment of the stay-hooks to the 20 frame in a substantially permanent way, and this makes it necessary for the operator to forcibly lift the heddle-bars over the hooks, which practice is objectionable for two reasons: First, the heddles are strained or 25 stretched lengthwise to such an extent that they are frequently broken or made useless, and, secondly, the application of force by the hands hurts them to such an extent that operators object to changing the heddles. 30 The object that I have in view is to provide means by which the adjustment, removal, and insertion of the heddles can be easily, quickly, and readily performed without hurting the hands of the operator, be- 35 cause it is not necessary to forcibly lift the heddle-bars and strain the heddles strung thereon. I attain these objects by the em- 40 ployment of a stay-hook which is removably attached to the heddle-frame and is easily slipped from engagement with the heddle-bars.

Further objects and advantages of the invention will appear in the course of the subjoined description, and the novelty will be 45 defined by the annexed claims.

Reference is to be had to the accompanying drawings, forming a part of this specification, in which similar characters of reference indicate corresponding parts in all the figures.

50 Figure 1 is an elevation, partly broken away, of a loom heddle-frame embodying my improvements. Fig. 2 is a detail cross-sec-

tion on the line 2-2 of Fig. 1, and Fig. 3 is a fragmentary view in elevation illustrating another embodiment of the invention. 55

5 designates an ordinary loom heddle-frame provided with detachable heddle-bars 6, the latter spanning the frame near the end portions thereof and secured removably to the side rails of the frame by any suitable means 60 known to the art. On the supporting-bars 6 are threaded any desired number of heddles 7, each having an eye 8, said heddles being of any suitable construction and fitted loosely on the bars 6. 65

In this art it is customary to employ means which serve to brace or stay the heddle-supporting bars 6. The stay means are usually in the form of hooks, which engage with the bars 6 and are fastened to the frame; but ordinarily the stay-hooks are fastened to the frame in such a way that they cannot be easily detached when it is desired to adjust or interchange the heddles. I overcome this difficulty by employing stay-hooks which are de- 75 tachably fastened to the frame in a way to facilitate the removal thereof from the heddle-supporting bars 6. In one embodiment of the invention I employ a series of stay-hooks 9, each of which is provided with a 80 shank formed with a recess 10, which thereby constitutes the hook. The other end of the stay-hook is provided with a transverse eye 11, and through the eyes of the series of hooks 9 is passed a rod 12, the latter being fastened 85 removably to the frame 5. This rod is braced by the employment of eyes on the frame, one of said eyes being indicated at 13 in Fig. 1, al- 90 though it will be understood that a series of the eyes is attached to each end bar of the frame in a position for the rod 12 to pass therethrough. The rod may be fastened re- 95 movably to the side bars of the frame in any suitable way; but, as shown by Fig. 1, the end portions of this rod are provided with nuts 14, which are screwed on said rod and bind against the outer edges of the frame. The series of stay-hooks are fitted loosely on the rod 12 in a way to have a slidable move- 100 ment thereon, and the entire series of these hooks may be disconnected simply by remov- ing the rod 12 and slipping the hooks from the heddle-supporting bars 6, thus allowing the heddles 7 to be shifted on the bars and

permitting either bar to be removed from the heddle-frame easily and quickly in order to interchange the heddles or increase or decrease the number thereof, as may be desired.

5 The employment of a single rod in connection with a series of stay-hooks serves to attach the series detachably to the frame; but my invention is not restricted to this attachment of the stay-hooks in series, because I am aware that the stay-hooks may be connected individually to the frame in a way to facilitate the removal thereof. One embodiment of means for individually fastening the 10 stay-hooks to the frame is represented by Fig. 3, wherein each stay-hook 9 is loosely and slidably fitted on a horizontal bolt 15, supported in a pair of eyes 16, that are fastened to the end rail of the frame. One end 15 of the rod or bolt 15 is provided with a head 17, while its other end receives a nut 18. In this construction the stay-hook 9 is free to slide on the rod or bolt 15 between the pair 20 of eyes 16, and said rod or bolt 15 can easily be detached from the eyes by removing the nut 18 and withdrawing the rod or bolt end- 25 wise, thus disconnecting the stay-hook 9 from the end bar of the frame and permitting the hook to be readily slipped away from the 30 heddle-supporting bar 6.

Having thus described my invention, I claim as new and desire to secure by Letters Patent—

1. A loom heddle-frame having heddle-sup-

porting bars, a rod or bolt fastened removably to said frame, and a stay-hook fitted to said rod or bolt and the heddle-supporting bar, whereby the rod or bolt may be withdrawn from the frame and the hook may be slipped from engagement with the heddle- 35 supporting bar.

2. A loom heddle-frame having heddle-supporting bars, a series of stay-hooks engaging with said bars, and a rod or bolt secured removably to the frame, said stay-hooks being 40 threaded on the rod or bolt and adapted on the withdrawal of said rod to be easily disengaged from the heddle-supporting bar.

3. A loom heddle-frame having heddle-supporting bars, a removable rod or bolt attached 45 to said frame, and a stay-hook loosely and slidably fitted on said rod or bolt and engaging removably with the heddle-supporting bar.

4. A loom heddle-frame having a heddle- 50 supporting bar, a rod or bolt secured removably to the frame, an eye fastened to the frame and engaging said rod or bolt, and stay-hooks threaded on the rod or bolt and engaging the heddle-supporting bar. 55

In testimony whereof I have signed my name to this specification in the presence of two subscribing witnesses.

RUDOLPH G. WIRTALLA.
